Primary Examiner — Darlington Ly*Assistant Examiner* — Nasim Abdulaziz Ali(74) *Attorney, Agent, or Firm* — Faegre Drinker Biddle & Reath LLP(57) **CLAIM**

The ornamental design for an all-terrain vehicle, as shown and described.

DESCRIPTION

FIG. 1 is a front and left side perspective view of an all-terrain vehicle embodying our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The portions of the vehicle and the vehicle components shown in broken lines form no part of the claimed design.
